United States Patent Office

Des. 203,260
Patented Dec. 21, 1965

203,260

VEHICLE WHEEL

Frank J. McNulty, P.O. Box 375, San Bernardino, Calif.

Filed Feb. 8, 1965, Ser. No. 83,740

Term of patent 7 years

(Cl. D14—30)

FIGURE 1 is a front elevational view of a vehicle wheel showing my new design; and FIGURE 2 is a transverse axial sectional view taken on the line 2—2 of FIGURE 1.

I claim:

The ornamental design for a vehicle wheel, as shown.
